223,829

EAVES TROUGH SHIELD

Frank M. Cook, 28854 E. River Road,
Perrysburg, Ohio 43551

Filed Oct. 2, 1970, Ser. No. 25,758

Term of patent 14 years

Int. Cl. D23—01

U.S. Cl. D23—42

FIG. 1-

FIG. 2-

FIG. 3-

FIG. 4-

FIG. 5-

FIG. 1 is a top plan view of an eaves trough shield embodying my new design;

FIG. 2 is a front elevational view thereof;

FIG. 3 is a bottom plan view thereof;

FIG. 4 is a rear elevational view thereof;

FIG. 5 is a cross sectional view taken on line 5—5 of FIG. 2; and

FIG. 6 is a front perspective view thereof.

I claim:

An ornamental design for an eaves trough shield, as shown.
